UNITED STATES PATENT OFFICE.

ERNST A. EIBAND, OF NEW BRAUNFELS, TEXAS.

BUTTER-CONTAINER.

1,070,238.

Specification of Letters Patent. Patented Aug. 12, 1913.

Application filed July 29, 1912, Serial No. 712,111. Renewed March 6, 1913. Serial No. 752,467.

To all whom it may concern:

Be it known that I, ERNST A. EIBAND, a citizen of the United States, residing at New Braunfels, in the county of Comal, State 5 of Texas, have invented certain new and useful Improvements in Butter-Containers; and I do hereby declare the following to be a full, clear, and exact description of the invention, such as will enable others skilled in 10 the art to which it appertains to make and use the same.

The present invention is directed to improvements in butter containers, and has for its object to provide a device of this character in which butter may be placed in the dairy and will thus be protected against handling until it is desired to serve the same upon the table.

A further object of the invention is to construct a container of this character which may be readily cleaned, and one which may be manufactured at a minimum cost.

With these and other objects in view, this invention resides in the novel features of 25 construction, formations, combinations and arrangements of parts to be hereinafter more fully described, claimed and illustrated in the accompanying drawing, in which:

Figure 1 is a perspective view of the container. Fig. 2 is a longitudinal sectional view through the same. Fig. 3 is a transverse sectional view. Fig. 4 is a detail perspective view of one of the ends removed from the container.

Referring to the drawing, the numeral 1 designates a bottom, and 2 a top, said top and bottom being connected by the sides 3, the ends of which project slightly beyond the ends of the sides, and are provided with 35 vertical grooves 4 for slidably receiving flanges 5 formed upon the side edges of the removable ends 6. The ends 6 are each kerfed as at 7, said kerf extending nearly the whole width of the ends. The ends are 40 further provided with registered circular apertures 8.

Adapted to be placed in the kerf 7 is a

wire mesh screen 9, the same being readily removable for cleaning or replacing the same when desired, and serves to ventilate the container. A filling strip 10 is placed in the slot 11 formed by kerfing the ends so that the screen 9 may be readily removed or replaced.

To prevent displacement of the strip 10 pins 12 are passed through the ends and through said strip, as clearly shown in Fig. 4 of the drawing.

The container is preferably made from wood, but it is to be of course understood that any other material may be substituted therefor if desired.

From the foregoing description, it will be seen that a container of this character has been produced upon which the date the butter was made may be stamped, without danger of the ink soaking through to the butter which frequently occurs when paper cartons are used. Further it will be noted that by making the container from wood the same 70 may be conveniently cleaned by dipping the same in salt water, and that they may be constructed at a minimum cost, and in sizes to suit all occasions.

What is claimed is:—

In a device of the class described, comprising a top and bottom, side and end walls connecting the same, said side walls having their ends projected beyond the ends of the top and bottom, vertical grooves formed in 80 the extended ends of the sides for slidably receiving the end sections, said end sections having kerfs formed therein, apertures formed in the ends, and arranged in registry with each other and wire screens detachably mounted in said kerfs, as and for the purpose set forth.

In testimony whereof, I affix my signature, in presence of two witnesses.

ERNST A. EIBAND.
